UNITED STATES PATENT OFFICE.

ROBERT C. TOTTEN, OF PITTSBURG, PENNSYLVANIA.

METHOD OF PROTECTING BUILDINGS FROM LIGHTNING.

No. 926,521.

Specification of Letters Patent.

Patented June 29, 1909.

Application filed July 27, 1908. Serial No. 445,608.

To all whom it may concern:

Be it known that I, ROBERT C. TOTTEN, a resident of Pittsburgh, in the county of Allegheny and State of Pennsylvania, have invented a new and useful Improvement in Methods of Protecting Buildings from Lightning; and I do hereby declare the following to be a full, clear, and exact description thereof.

10 My invention relates to means for protecting oil tanks, refineries, barns, churches, and other buildings from lightning. It is a well known fact that such tanks or buildings are usually isolated, having a good deal of space around the same, the buildings projecting above the general level of the ground, being thus especially exposed to the rays of the sun. It is believed that such buildings are liable to be struck by lightning owing to the formation 15 of a rarefied column of air caused by the rays of the sun striking upon the building as it stands above the level of the ground, causing a rarefied column of air above the same, and that the lightning follows the line of least 20 resistance and therefore is liable to pass down the rarefied column of air and strike the building.

The object of my invention is to prevent such action, and it consists in cooling the top 25 of the building, such as by agitation of the air above the building and thereby keeping the air more in equilibrium with the surrounding atmosphere.

The invention is illustrated in the accompanying drawing in which—

Figure 1 is a diagrammatic view of an oil tank with the preferred form of the invention applied thereto, such as fans for agitating the air; and Fig. 2 is a view of a building in which 30 water cooling is applied.

In said drawing the tank 1 has located around the same a series of fans 2 which, as illustrated, can be driven by electric motors 3, and which are preferably so placed as to 35 draw the air from beyond the tank and force

it over the surface of the tank, thereby both cooling the top surface of the tank and agitating the air above the same and in such way preventing the formation of a column of rarefied air above the tank and keeping the 40 air above the tank more in equilibrium with the surrounding atmosphere.

In Fig. 2 I have illustrated the invention as carried out by water cooling, in which 4 is a building having the roof 5 and perforated 45 pipes 6 located near the apex of the roof from which a spray of water can be thrown over the surface of the roof and extending over the same for some distance, the water from the spray dropping down over the surface of 50 the roof into the regular gutters 7. In this way the roof of the building is maintained cool, so that the rays of the sun striking the same will not be liable to form a rarefied column of air above the same, and at the same 55 time the spraying of water will cause the formation of cross currents of air which will tend to maintain the equilibrium of the air above the building with that surrounding the same.

The above are illustrations of the general invention and which of course can be practiced in any suitable way.

What I claim is:

1. The method of protecting buildings 60 from lightning, consisting in keeping the roofs thereof cool.

2. The method of protecting buildings from lightning, consisting in keeping the roofs above the buildings cool by agitating 65 so the air above the buildings.

3. The method of keeping the roofs of buildings cool, consisting in forcing the air over the roofs of the buildings.

In testimony whereof, I the said ROBERT 70 C. TOTTEN have hereunto set my hand.

ROBERT C. TOTTEN.

Witnesses:

G. H. RANKIN,
J. R. KELLER.
